UNITED STATES PATENT OFFICE.

CHARLES H. GRIFFIN, OF CLEBURNE, TEXAS.

DEVICE FOR HANDLING MARBLE SLABS.

1,103,409.

Specification of Letters Patent. Patented July 14, 1914.

Application filed November 20, 1913. Serial No. 802,140.

To all whom it may concern:

Be it known that I, CHARLES H. GRIFFIN, a citizen of the United States, residing at Cleburne, in the county of Johnson, State 5 of Texas, have invented certain new and useful Improvements in Devices for Handling Marble Slabs; and I do hereby declare the following to be a full, clear, and exact description of the invention, such as 10 will enable others skilled in the art to which it appertains to make and use the same.

This invention relates to devices for handling marble slabs in such a manner as to safely transport the same manually from 15 place to place without danger of scratching the same.

The primary object of the present invention is to provide a holder having a pair of jaws operatively connected with grips 20 whereby upon the laborer grasping the grips and raising the slab the jaws will automatically tighten frictionally against the slab and secure the latter against escape.

A further object of the invention is to 25 provide jaws having rounded yielding working faces which engage with the surface of the slab without mutilating the same.

With the above objects in view the invention consists of certain novel details of construction and combination of parts herein- 30 after fully described and claimed, it being understood that various modifications may be made in the minor details of construction within the scope of the appended claims.

35 In the accompanying drawing illustrating this invention:—Figure 1 is a side elevation showing a pair of my improved holders applied to a slab. Fig. 2 is a plan view of the parts shown in Fig. 1. Fig. 3 is a perspective view of one of the holders. Fig. 4 is a cross sectional view on the line 4—4 40 Fig. 1, showing the pivot and the grip of one of the jaws.

Referring now to the drawing in which 45 like characters of reference designate similar parts, 10 designates a marble slab and 11 and 12 designate a pair of holders receiving an end edge portion of the slab therebetween whereby a laborer may grasp the 50 grips of the holders and carry the slab to any desired place. Each holder comprises a U-shaped frame including cylindrical sides 13 which form pivot shafts for the jaws to be subsequently described, the sides being 55 braced by a cross brace 14, and there being a substantially U-shaped frame 15 carried

by the first named frame near the bottom thereof—and projecting at a slight angle to the latter, the bridge member 16 of this frame being faced with a rubber sleeve 17 60 adapted for engagement with the edge of the slab. Pivoted eccentrically on each pivot shaft 13 is a jaw 18 that is provided with an arcuate working face covered with a yielding element 19 of any desired type. A 65 stem 20 projects from the rear face of the jaw and is disposed to one side of the pivot shaft as shown, there being a grip 21 provided with a stem 22 that is pivoted as shown at 23 to the outer end of the stem 20. 70

In applying the holder to the slab, the operator passes the jaws one on either side of the slab until the stop frame sleeve 17 engages with the edge of the slab. In this position one grip of the tool will be disposed 75 on one side face of the slab while the other grip will be disposed on the opposite side face of the slab. Two of these tools are applied as above described, one to each vertical end edge of the slab, there being then a grip 80 of each tool disposed on a common face of the slab whereby a workingman may grasp such grips in his hands. Upon both workingmen lifting, the jaws of both tools will be automatically tightened frictionally 85 against the slabs with a resultant anchoring of the tools to the slab so that the latter may be transported with ease and quickness. During such transportation, by virtue of the working faces of the jaws being 90 covered with yielding surfaces, the tools will not scratch or mutilate the marble.

From the above description it will be seen that I have provided an extremely simple and inexpensive while at the same time 95 strong and durable tool of the character described which will be formed of a few parts that will not easily get out of order.

What is claimed, is:—

1. A slab gripping tool including a frame 100 having the sides forming pivot shafts, a pair of opposed jaws eccentrically mounted on said pivot shafts, a stop frame carried by the first named frame and projecting across a prolongation of the space between 105 said jaws, and grips mounted on said jaws.

2. A slab gripping tool including a frame having the sides forming pivot shafts, a pair of opposed jaws eccentrically mounted on said shafts and each having an arcuate 110 yielding working face, a stop frame carried by the first named frame and projecting

across a prolongation of the space between said jaws, and grips carried by said jaws.

3. A slab gripping tool including a frame having the sides forming pivot shafts, a pair of opposed jaws eccentrically mounted on said shafts, a stop frame carried by the first named frame and projecting at a slight angle thereto and extending across a prolongation of the space between said jaws, and grips carried by said jaws.

4. A slab gripping tool including a frame having the sides forming pivot shafts, a pair of opposed jaws eccentrically mounted

on said shafts, a stop frame carried by the first named frame and projecting across a 15 prolongation of the space between said jaws, and a grip on each jaw including a stem projecting from the jaw on one side of said pivot shaft, and a hand hold pivotally secured to said stem. 20

In testimony whereof, I affix my signature, in the presence of two witnesses.

CHARLES H. GRIFFIN.
